UNITED STATES PATENT OFFICE.

JAMES R. BRADSHAW, OF MANCHESTER, TENNESSEE.

WATER-POWER DEVICE.

Application filed February 1, 1922. Serial No. 533,331.

To all whom it may concern:

Be it known that JAMES R. BRADSHAW, a citizen of the United States, residing at Manchester, in the county of Coffee and

5 State of Tennessee, has invented certain new and useful Improvements in Water-Power Devices, of which the following is a specification.

This invention relates to new and useful 10 improvements in water power devices, the primary object of the invention being to provide a device which will obtain the maximum power from a water-fall.

Another important object of the invention 15 is to provide a water power device actuated by the weight and force of a water-fall, the arrangement of the power device being such as to retain the same under the influence of a predetermined amount of the water-fall 20 so as to obtain the maximum power therefrom.

Another object of the invention is to provide a water power device including an endless belt disposed in the path of a water-fall 25 and having associated therewith buckets of a particular construction, whereby they are locked against movement during a portion of their travel around the endless belt.

A further object of the invention resides 30 in the provision of means associated with the buckets of the endless belt whereby water overflowing from one bucket will be directed into the next lowest bucket.

Other objects and advantages of the invention 35 will become apparent during the course of the following description.

In the accompanying drawings forming 40 a part of the description and wherein like numerals are employed to designate like parts throughout the several views:

Figure 1 is a vertical section through the power device.

Fig. 2 is a top plan of the water power device.

45 Figure 3 is a perspective view of a bucket.

Figure 4 is an elevation of a portion of a dam used in one embodiment of the invention.

Figure 5 is an elevation of the opposite 50 side thereof.

Figure 6 is a fragmentary side elevation of a detail of the invention.

Figure 7 is a side elevation of a bucket and a portion of the web, and

55 Figure 8 is a fragmentary longitudinal section thereof.

In the drawings, wherein for the purpose of illustration is shown the preferred embodiment of my invention, the numeral 7 designates a dam created by a head wall 8 60 and it is to be understood that one or more discharge openings 9 may be provided therein, adjacent the top thereof, so that a plurality of power devices may be associated with the head wall. However, as all of the 65 discharge openings and power devices are the same in construction, a description of one will suffice for all.

In order that the flow of water through the discharge openings 9 may be controlled 70 at will, a vertically slidable gate 10 is associated with each opening and is mounted in a guide 11, attached to the inner face of the head wall 8. This gate 10 may be controlled by any medium desired, but preferably by 75 means of a shaft, not shown, extending across the dam above the head wall. This shaft winds and unwinds the chain 12, the lower end of which is secured to the upper end of the gate 10. When a plurality of 80 gates are associated with the head wall, it will be seen that by this construction all of them may be controlled simultaneously.

A pair of water chutes are associated with each discharge opening 9 in the head wall 85 and are fastened therein. The uppermost chute 13 is disposed in an approximately horizontal position as in the lower chute 14, but the outlet end of the latter is inclined slightly downwardly, as clearly shown in 90 Figure 1. The outlet ends of these two chutes are braced by interposing a brace between them, as clearly seen.

The power device, indicated in its entirety by the numeral 15 is supported between a 95 pair of walls 16, projecting laterally from the outer face of the head wall 8, as clearly seen in Figures 1 and 2. This power device preferably consists of an endless web 16', which is trained over upper and lower 100 pairs of sprockets 17 and 18, the lower pair being smaller and having their axle arranged closer to the head wall than the shaft carrying the upper pair of sprockets, so that the run of the web adjacent the head 105 wall will be arranged perpendicular and the other run will incline upwardly and outwardly of said wall. The upper pair of sprockets 17 are spaced and keyed to a shaft 18' which is journaled in a pair of 110 bearing boxes 19, mounted on the top of the side walls 16. A pulley wheel 20 is

likewise keyed to the shaft, whereby power created by the power device may be transmitted to other machinery. The lower pair of sprockets 18 are likewise keyed to a lower, transverse shaft 22, opposite ends of which are mounted in boxes 22' which are slidably mounted in vertical, elongated slots 23 provided in the side walls 16. The boxes 22' are normally arranged in the upper ends of the slots and it will therefore be seen that the uppermost shaft 18' supports the entire weight of the power device.

At this point, it will be well to set forth that I do not desire to limit the application of the power device to dams, since obviously it may be applied to natural waterfalls and the endless web 16' may be made as long as the water-fall is high, so that one run of the web may be disposed the full length of the water-fall, whereby this run of the web will be under the influence of the water-fall continuously.

The endless web 16' in the present instance comprises a pair of endless linked chains, the links of the pair of chains being pivotally connected by transversely arranged rods 25. The ends of these rods are reduced as seen in Fig. 8 and are threaded to extend through the links of the chains to connect the same. Nuts are screwed upon the reduced ends of the rods to prevent displacement of the links.

A plurality of buckets or containers 26 are adapted to be associated with the endless web in a manner that their mouths will be disposed uppermost to receive water along one run of the web and the mouths of the buckets will open downwardly along the other run of the web for discharging water therefrom. Each receptacle consists, generally of a hollow cylindrical member, the end walls of which are each provided with a pair of apertures, whereby the reduced ends of the rods 25 of the web may extend therethrough for mounting the receptacle upon the web. A portion of each hollow cylindrical receptacle is removed as at 27, to provide the same with a mouth, and the end walls of each receptacle are extended, as at 28, to provide the receptacle with a bill or abutment. The body portion of the receptacle adjacent these extensions of the side wall is also extended, as at 29, to rest upon and be fastened to the inner edges of the end walls 28. The purpose of this particular construction of the buckets is to provide for the stability of the buckets along the perpendicular run of the web, which is disposed adjacent the discharge chutes of the head wall. It will be seen that the buckets on the inner run of the web will be disposed with their mouths uppermost and with their end walls 28 in contact with the receptacle arranged thereabove to prevent the inflowing water from the chutes

from causing the buckets to tilt away from the chutes.

The front wall of each bucket slightly below the mouth thereof is provided with an overflow attachment in the form of a deflector plate 30 curved in the same direction as the front wall of the bucket and spaced therefrom so that any overflow from one bucket will be directed into the mouth of the next lower bucket. With this arrangement it will be seen that when all buckets are empty and it is desired to start the device, water is permitted to enter the bucket adjacent the chutes 13 and 14. When this bucket has been filled the water will overflow and be directed by the overflow attachment of the bucket into the next lowest bucket and so on down the run of the web until sufficient water is carried by the buckets of the run to set the web into motion.

In operation, and assuming that the water gate 10 has been opened, it will be seen that the water in the dam will rush through the discharge chutes 13 and 14 and be directed into the bucket or receptacle 26 arranged closest to the chutes. These chutes, are of course, disposed close enough to the receptacles so that all of the water discharging therefrom will be directed into the adjacent receptacle and thence to the buckets thereunder as explained above. As all of the buckets on the outer run of the web are caused to empty by the inclined position of the outer run, it will be seen that the web will be caused to move in a counter clockwise direction. As the web begins to move, it will be seen that the buckets will be successively brought into a position to receive water from the discharge chutes 13 and 14 and after the power device has been put into operation for a limited time, and more and more weight is added to the inner run of the web by the buckets becoming full of water, it will be obvious that the web will obtain considerable speed and transmit the power derived from the water to the pulley wheel 20 from where the power may be conveyed to any suitable machinery.

It will be noted that the lowermost discharge chute 14 is directed downwardly, so as to discharge water directly into the bottom of each receptacle, while the uppermost discharge chute 13, which is arranged in a horizontal position, will direct water therefrom to the extended portion 29 of the receptacle to direct such a force thereon as to retain the same in contact with the receptacle above. The buckets each being connected to the web by means of a pair of rods 25, it will be seen that as soon as the rods of any one bucket reach either sprocket wheel, the receptacle mounted thereon will begin to tilt and the buckets passing around the lower sprocket wheel 18 will be caused to

discharge water therefrom, while those coming up over the sprockets 17 will be caused to assume position whereby their mouths will be disposed uppermost and in a position to receive the water discharging from the chutes 13 and 14.

The foregoing description and the accompanying drawings have reference to the preferred or approved embodiment of my invention. It is to be understood however, that such changes may be made in construction and arrangement of parts, materials, dimensions, etc., as may prove expedient and fall within the scope of the appended claims.

Having thus described and illustrated my invention, what I now claim as new and desire to secure by Letters Patent is:

1. A water power device comprising an endless web, buckets associated therewith, each bucket consisting of a hollow cylindrical member having a portion of its curved wall removed to form a throat or inlet opening and each cylindrical member being provided with an abutment adjacent said inlet opening to engage an adjacent bucket for preventing the first named bucket being tilted by water entering the same.

2. A water power device comprising an endless web, a plurality of buckets attached thereto, each bucket comprising a hollow cylindrical member arranged in close proximity to the other buckets on the web, each cylindrical member having a water inlet opening and a portion of said member extended to form a back for said opening and an abutment for engagement with the bucket above.

3. In combination, a dam having a pair of water discharge chutes associated therewith, one of the chutes being directed approximately horizontally, and the other chute being directed slightly downwardly; of an endless web disposed in proximity to the chutes, a plurality of buckets carried by the web, said bucket each being adapted to abut the next adjacent bucket at certain times, the buckets of the inner run adapted to receive water from the chutes, the horizontally disposed chute being adapted to discharge water against the extensions of the buckets to retain them in engagement with one another.

4. A water power device comprising in combination an endless web, a plurality of buckets associated therewith, each bucket consisting of a hollow cylindrical member having an opening in its side to form a water inlet opening, an extension provided on each cylindrical member and adapted to abut with the bucket above at intervals; of a source of water supply including a pair of chutes, one of said chutes being arranged horizontally to discharge water against said extensions of the buckets to retain the same in engagement with the bucket above, and the other chute being inclined downwardly to discharge water onto the bottom of said buckets.

In testimony whereof I affix my signature in presence of two witnesses.

JAMES R. BRADSHAW.
